ASH SMELTER

Adolph W. Waern, Manistee, Mich.

Application November 12, 1932, Serial No. 642,351

4 Claims. (Cl. 23—277)

This invention relates to smelters for igniting and removing the organic content of black ash and the like.

The invention comprises a novel structure in which combustion of the black ash is maintained within the confines of a complete independent vapor-raising apparatus or boiler. The boiler is arranged in such a manner that considerable portions of its heating surface can "see" the fire and accept heat therefrom not only by conduction and convection but also by radiation. The boiler being so arranged accepts heat from the smelting ash at such rates that favorable temperatures are maintained with the greatest ease. The apparatus of this invention not only provides means for excellent control of operating conditions, but also converts the heat absorbed in controlling the process into vapor under pressure which may be devoted to superior power uses.

The recovery of mineral substances employed in paper-making processes is an important matter in the economy of the pulp industry. Waste liquors from the sulfate and soda processes, for example, have long been evaporated to dryness and the dried material ignited to separate therefrom the mineral constituents usually in a molten state. The recovered mineral constituents upon proper subsequent treatment are rendered fit for re-use.

The ignition step has been performed in the apparatus known as a smelter. The smelters heretofore used, however, are open to some objection and it is the purpose of this invention to dispense with the undesirable features thereof.

One of the chief objections in many of the smelters now in use is that entirely satisfactory refractory linings which will withstand the erosion of the fire and the effect of the highly alkaline salts involved in the treatment have not been available. Many attempts have been made and some are now in use for prolonging the life of smelter linings. In some of these a refractory layer is backed by a circulating layer of air for the purpose of keeping the lining below a dangerous temperature. In others cooling water is circulated in much the same manner with the same purpose. In many of these methods the heat removed from the walls is either rejected or devoted to inferior uses.

In the smelter of this invention portions of the interior constituting part of the heat-accepting surfaces of the boiler are devoid of refractory material, in the common sense of the word, and in this portion of the smelter the refractory lining problem is completely eliminated. Not only is the smelter of this invention cheaper to maintain

with respect to its lining, but at the same time the heat absorbed is converted into a steam at useful pressure. Although the smelter of this invention is particularly adapted for use in the treatment of the ash produced by the evaporation of the waste liquors of the sulphate and soda paper processes any combustible solid or semi-solid material having a mineral content may be treated.

The smelter of this invention is best described by reference to the accompanying drawings wherein

Fig. 1 is a side sectional view of the smelter;

Fig. 2 is a front view of the smelter, part of the jacket being broken away.

The smelter of this invention, as shown in Fig. 1, is mounted upon a suitable support 1. Firmly seated upon support 1 and inside of the smelter is the crucible 2, made of refractory material. The crucible 2 is provided with wall portions 3, a spout portion 4 and a base portion 5. Standing upon base 1 and embracing the wall portions 3 of the crucible and extending upwardly is the tube bank 6. Forming the means for communication for the bottom of the tube bank is the header 7. The tube bank 6 extending upwardly converges into a flat throat 9 and thence reaches upwardly to a connection with the vapor drum 10. On one side of the flat throat 9 an aperture 11 is provided by joining a part of the tubes of bank 6 to manifold 12, which in turn communicates with the vapor drum 10 through leaders 18.

Completely enclosing tube bank 6 is the mantle 13, the purposes of which are to form a gas-tight enclosure outside of bank 6 and to insulate against the loss of heat. Any suitable material may be used for this purpose, most of the common refractory materials serving well. The mantle 13 is backed and supported by a steel shell 14 which is separated a short distance from the mantle to provide for expansion. The expansion space is filled with any suitable resilient refractory 15, such as asbestos or powdered diatomaceous earth. It is pointed out as a matter of importance that the bank 6 is not entirely hidden by a lining, but that a goodly part of each tube can "see" the interior of the smelter.

From the vapor drum 10 downcomers 17 are provided, which communicate with the header 7 at the base of the smelter to provide means for facilitating circulation. Feed water may be introduced in the lower part of one of these downcomers at 21 or in any other appropriate place. Vapor is removed from the top of the vapor drum at 20.

The blast is directed into the smelter in the

vicinity of the upper central portion of the crucible 2 through the nozzles or blow-pipes 22. The nozzles or blow-pipes 22 may advantageously be water-cooled.

5 As clearly indicated in Fig. 2, aperture 11 is circular in shape. The purpose of this aperture is to accommodate the discharge end of a conventional rotary drum incinerator, as shown in dotted lines in Fig. 1. The construction of the drum and of
10 the juncture between drum and smelter is no part of this invention, being similar in construction to means well known in the art.

Under many conditions of operation, blasting of the smelter produces combustible gas in the
15 nature of producer gas. Air for combustion of this gas may be introduced in the throat 9 and for this purpose doors 16 are provided for the entrance of air. By regulation of doors 16 the flame may be caused to extend far into subsequent equipment.
20 In addition to doors 16 air ports 23 are provided between the tubes in the lower part of throat 9. The air ports are provided with adjustable doors 24 to permit the regulation of the air admitted.

In addition to the air ports 23 and the doors 16
25 it is sometimes convenient also to provide poke holes 25 closed by doors 27. If it is intended to employ poke holes 25 for anything other than inspection and regulation of the fire, the tubes may be appropriately deflected to permit the
30 charging of material or chemicals. In fact the smelter of this invention may be so constructed that it may be operated as a hand-fired or conveyor-fired smelter in which the aperture 11 is closed and occupied by tubes, all charging then
35 being accomplished through openings, such as poke holes 25. A construction such as above described of course does not require a broad, flat throat 9 such as will accommodate the large circular aperture 11 and in such case the throat 9
40 will become a mere vertical extension of the lower part of the smelter.

In operating the smelter of this invention organic material containing mineral substance is charged through aperture 11. Combustion of the
45 organic material is established by introducing a blast of air through the nozzles or blow-pipes 22. Blasting and charging of material are then continued at rates which will maintain a substantially constant depth of burning material. While this
50 is taking place the temperature is controlled by the boiler and useful vapor is delivered to drum 10. As the material is consumed the mineral constituents are released and due to the heat of the reaction they are delivered in molten condition to
55 the crucible 2. From time to time or continuously the molten material is discharged from the spout 4 into appropriate equipment. In the paper art one common practice is to discharge the molten material directly into water to effect solution thereof. This solution is then treated and prepared for re-use in the manufacture of pulp.

While the use and construction of the smelter of this invention has been clearly indicated in certain specific cases, it is not intended that the
65 protection of Letters Patent be limited thereby, but that the protection afforded hereunder embrace the full spirit of the invention as represented by the appended claims.

70

75

What I claim as my invention is:

1. In a combined self-contained vapor generator and smelter for organic, inorganic mixtures, the combination comprising a crucible, a mantel surrounding and extending above said crucible, a tube bank within said mantel and extending downwardly between the exterior of said crucible and the interior of the lower part of said mantel, means for supplying fluid to the interior of said tube bank, and means for removing vapor therefrom.

80 2. In a combined self-contained vapor generator and smelter for organic, inorganic mixtures, the combination comprising a crucible, means for introducing a blast in the vicinity of said crucible, a mantel surrounding said crucible and extending above the same, an opening into said mantel above the crucible for the introduction of material to be treated and the exit of products of combustion, a tube bank within said mantel and extending downwardly between the exterior of said crucible and the interior of the lower part of said mantel, means for introducing vaporizable fluid to said tube bank, and means for removing vapor therefrom.

85 3. In a combined self-contained vapor generator and smelter for organic, inorganic mixtures, the combination comprising a crucible, means for introducing a blast in the vicinity of said crucible, a mantel surrounding said crucible and extending above the same, an opening into said mantel above the crucible for the introduction of material to be treated and the exit of products of combustion, a tube bank within said mantel consisting of vertically standing tubes and extending 90 downwardly between the exterior of said crucible and the interior of the lower part of said mantel, means for establishing communication between the bottoms of said tubes, a vapor drum communicating with and joining the tops of said tubes, 95 means for introducing feed-water, and means for the removal of steam from said steam drum.

100 4. In a smelter for organic, inorganic mixtures, the combination comprising a crucible having an outlet, a mantel surrounding said crucible and extending above the same, means for introducing a blast of air in the vicinity of said crucible, an aperture in the top of said mantel for the introduction of material to be treated and the exit of products of combustion, a tube bank of 105 vertically standing tubes within said mantel and extending downwardly between the exterior of said crucible and the interior of the lower part of said mantel, means for establishing communication between the bottoms of said tubes, a steam drum in communication with and joining the tops 110 of said tubes, downcomers communicating with said steam drum and connecting with the communication means at the bottom of said tubes completing a boiler enclosure, means for the introduction of vaporizable fluid to said boiler enclosure, and means for the removal of vapor from 115 said steam drum, the whole forming a combined self-contained vapor generator and smelting furnace.
